UNITED STATES PATENT OFFICE.

CHARLES B. SCHOENMEHL, OF WATERBURY, CONNECTICUT.

PRIMARY BATTERY.

1,055,562.

Specification of Letters Patent. Patented Mar. 11, 1913.

Application filed May 3, 1912. Serial No. 694,884.

To all whom it may concern:

Be it known that I, CHARLES B. SCHOENMEHL, citizen of the United States, and resident of Waterbury, in the county of New Haven and State of Connecticut, have invented certain new and useful Improvements in Primary Batteries, of which the following is a specification.

This invention relates to a simple and improved form of caustic solution battery, adapted for track circuit work and employed for operating bells, block signals and the like.

It further relates to primary batteries of that class wherein oxid of copper and zinc are employed in said solution and arranged one above the other, distant from each other.

A further purpose of the invention is to so arrange the elements that they will be insulatively connected and supported one from the other and finally to form the elements so that they may be readily inserted into or removed from the jar and also rigidly supported therein so as to prevent disassembly.

Similar characters of reference will be found to designate like or corresponding parts throughout the several figures and of which,

Figure 1, shows a sectional perspective view of my present form of track circuit battery with the elements resting upon the bottom of the jar. Fig. 2, is a plan view of the assembled electrodes shown in Fig. 1, and, Fig. 3, shows a further sectional perspective view of my battery, the assembled electrodes of which are shown supported from the top or cover of the jar instead of being supported from the bottom of the jar as shown in Fig. 1.

Referring in detail to the characters of reference marked upon the drawings, 5 represents a battery jar which as shown in Fig. 1, has no cover, but which in Fig. 3, is provided with a cover 6. The positive electrode 7 and negative electrode 8 are connected and supported one from the other through the medium of a frame 9 which is preferably made of a single strip of sheet metal that is bent and formed to connect the electrodes one above the other, distant from each other. This frame includes the two vertically disposed side portions 10—10, a horizontal top cross or bridge portion 11. The lower ends of the sides 10 are bent and secured to the metal receptacle 12 in a way

to form legs 13—13. One or more additional legs 14, may also be secured to this receptacle to better support the intermediate side portions to said receptacle as is clearly shown in Fig. 1. The receptacle 12 is formed in part of a sheet metal pan having a perforated sheet metal top or covering 15, and is filled with oxid of copper as shown, and thus constitutes the negative electrode. As shown in the drawings this electrode is arranged adjacent to the bottom of the jar and supported in the frame 9 before mentioned, and which frame in turn may be supported from the bottom of the jar as shown in Fig. 1, or from the cover as shown in Fig. 3.

I preferably employ the circular form of zinc electrode 7, which is hung from the cross portion 11 of the frame by means of a pair of short rods 16, secured to the zinc and extended upward therefrom and passing through insulating washers 17 of the frame where they are secured in said position by means of nuts 18. The field wire 19 connecting with the zinc pole of the battery, may be attached to one of these rods 16 by means of a suitable nut as shown. The centrally arranged rod 20 is secured to the cross member 11 of the frame and to it is attached the second field wire 21 by means of which the electrical connection with the negative electrode is formed through the said frame. The side members 10 of the frame are bowed out to yieldably engage the opposite side portions of the jar to support the element central and rigid therein. In Fig. 3, the terminal 20 also serves as a suspending rod, by means of which the assembled electrodes are hung from the cover 6 of the jar, and may be attached to or removed from the cover by the operation of the nuts upon the rod, and thus made to hang free of the jar as shown. The perforated side of the negative electrode receptacle is obviously arranged adjacent to, but below the zinc electrode and is thus arranged to properly connect therewith in the effective operation of the battery, and further protects the copper from any sediment from the zinc element above.

Having thus described my invention what I claim and desire to secure by Letters Patent is:—

1. In a track circuit battery of the class described, the combination of a rectangular shaped supporting frame, a negative elec-

- trode comprising a flat metal container with perforations in its top side and arranged in the bottom of a battery jar and secured to the lower part of the frame, a filling of oxid 5 of copper within the container, a zinc electrode arranged above the negative electrode and distant therefrom, and secured to the upper part of the frame.
2. In a track circuit battery of the class 10 described, the combination of a negative electrode, a zinc electrode, a supporting frame connected with and supporting each of the said electrodes and having longitudinally disposed strips that are bowed out to engage 15 the side walls of a jar to center and support the electrodes, and means for supporting the frame and electrodes within a jar.
3. In a primary battery of the class 20 described, the combination of a suitable supporting frame adapted to engage the inner walls of a jar, a horizontally arranged zinc electrode hung from the frame, a horizontally arranged metal container supported upon the frame and having its side adjacent 25 to the zinc perforated, a filling of oxid of copper in the container, and means for supporting the frame within a jar.
4. In a track circuit battery of the class 30 described, the combination of a negative electrode comprising a flat metal container with perforations in one side and arranged in the bottom of a battery jar, a filling of oxid of copper within the container, a zinc electrode 35 arranged above the negative electrode and distant therefrom, and a metal strip connected with both electrodes for supporting one electrode from the other.

5. In a primary battery of the class described, the combination of a suitable supporting frame, a zinc electrode mounted in the frame, a perforated metal container also supported in the frame and having means for supporting it in a battery jar, a filling of oxid of copper in the container, and means for supporting the zinc electrode from 40 and above the negative electrode within a jar. 45

6. In a primary battery of the class described, the combination of a frame adapted to be supported in a battery jar and to engage its side walls, a zinc electrode mounted in the upper part of the frame, a metal container supported in the lower part of the frame and jar and having its side adjacent to the zinc perforated, a filling of copper 50 oxid in the container. 55

7. In a primary battery of the class described, the combination of a frame adapted to be supported upon the bottom of a jar and also engaging the side walls of a battery jar, a zinc electrode mounted in the frame, a metal container supported in the lower part of the frame and jar and having its side adjacent to the zinc perforated, a filling of copper oxid in the container, and 60 means for supporting the frame within a jar. 65

Signed at Bridgeport in the county of Fairfield and State of Connecticut this 24 day of April A. D., 1912.

CHARLES B. SCHOENMEHL.
